US00D546219S

(12) **United States Design Patent** (10) **Patent No.:** **US D546,219 S**
Juteau (45) **Date of Patent:** **** Jul. 10, 2007**

(54) **SCALE**

D521,880 S * 5/2006 Drew et al. D10/91
D522,895 S * 6/2006 Petrucci D10/92

(75) Inventor: **Patrick Juteau**, Rumilly (FR)

* cited by examiner

(73) Assignee: **Tefal** (FR)

Primary Examiner—Antoine D. Davis
(74) *Attorney, Agent, or Firm*—Robert F. Zielinski; Wolf Block Schorr & Solis-Cohen, LLP

(**) Term: **14 Years**

(21) Appl. No.: **29/240,248**

(57) **CLAIM**

(22) Filed: **Oct. 11, 2005**

The ornamental design for a scale, as shown and described.

(30) **Foreign Application Priority Data**

Apr. 12, 2005 (FR) 05 1923

DESCRIPTION

(51) **LOC (8) Cl.** **10-04**

FIG. 1 is a perspective view of the scale showing my design.

(52) **U.S. Cl.** **D10/91; D10/92**

FIG. 2 is a top view of the scale of FIG. 1.

(58) **Field of Classification Search** D10/87-95;

177/4, 25.12-25.16, 177, 199, 210 R, 238-245,

177/DIG. 3, 262, 210 C, 30, 126-127; 324/692,
324/512, 515, 806; 600/506, 547

FIG. 3 is a bottom view of the scale of FIG. 1.

See application file for complete search history.

FIG. 4 is a front view of the scale of FIG. 1.

(56) **References Cited**

FIG. 5 is a left side of the scale of FIG. 1.

U.S. PATENT DOCUMENTS

FIG. 6 is a right side of the scale of FIG. 1; and,

D458,552 S * 6/2002 Ekelund D10/91

FIG. 7 is a rear view of the scale of FIG. 1
